US00D576624S

(12) **United States Design Patent**
Ashida et al.

(10) **Patent No.:** US D576,624 S
(45) **Date of Patent:** ** Sep. 9, 2008

(54) **CONTROLLER FOR ELECTRONIC GAME MACHINE**

(75) Inventors: **Kenichiro Ashida**, Kyoto (JP); **Junji Takamoto**, Kyoto (JP); **Masato Ibuki**, Kyoto (JP); **Shinji Yamamoto**, Kyoto (JP); **Hirokazu Matsui**, Kyoto (JP); **Daisuke Kumazaki**, Kyoto (JP); **Akiko Suga**, Kyoto (JP)

(73) Assignee: **Nintendo Co., Ltd.**, Kyoto (JP)

(**) Term: **14 Years**

(21) Appl. No.: **29/290,313**

(22) Filed: **Nov. 16, 2007**

Related U.S. Application Data

(63) Continuation of application No. 29/253,815, filed on Feb. 14, 2006, now Pat. No. Des. 559,254.

(57) **CLAIM**

The ornamental design for a “controller for electronic game machine,” as shown and described.

DESCRIPTION

FIG. 1 is a front, bottom and right perspective view of a controller for electronic game machine showing our new design;

FIG. 2 is a rear, top and left perspective view thereof;

FIG. 3 is a front view thereof;

FIG. 4 is a rear view thereof;

FIG. 5 is a right side view thereof, a left side view being a mirror image thereof;

FIG. 6 is a top plan view thereof; and,

FIG. 7 is a bottom plan view thereof.

The broken lines, which define the boundary of the claimed design, form no part thereof. The broken lines environmental are for illustrative purpose only and form no part of the claimed design.

1 Claim, 3 Drawing Sheets
